(57) **CLAIM**

I claim the ornamental design for a Pilates reformer, as shown and described.

DESCRIPTION

FIG. 1 is a first upper perspective view.

FIG. 2 is a second upper perspective view.

FIG. 3 is a lower perspective view.

FIG. 4 is a right elevation view.

FIG. 5 is a left elevation view.

FIG. 6 is a rear elevation view.

FIG. 7 is a front elevation view.

FIG. 8 is a top plan view; and,

FIG. 9 is a bottom plan view.

1 Claim, 8 Drawing Sheets
